United States Patent Office.

DANIEL F. WALLACE, OF RIPLEY, OHIO.

Letters Patent No. 77,553, dated May 5, 1868.

IMPROVED HEMP-BREAK.

The Schedule referred to in these Letters Patent and making part of the same.

TO WHOM IT MAY CONCERN:

Be it known that I, DANIEL F. WALLACE, of Ripley, Brown county, in the State of Ohio, have made new and useful Improvements in Hemp and Flax-Breaks; and I hereby declare the following to be a full and exact description of the same, reference being had to the drawings that accompany and form a part of these specifications.

The object of my invention is to provide a machine for breaking hemp or flax, to be operated by hand or other power, simple in its structure, and at the same time efficient in its operation.

Figure 1 is a perspective view.

Figure 2, top view of my machine, with the upper part or cover removed.

Figure 3, view of the spring-rest D, when arranged in sections.

Letter A, frame supported on four standards; letter B, rotating shaft resting on the frame A; letters C C, beating-wings attached to the shaft B; letter D, spring-rest for the hemp; letters E E, springs operating on the rest D; letters F F, inclines resting on the frame A, and provided with inclined slots *i i*, in which the ends of the rest, D, are supported and allowed to move back and forth; letter H, top or cover of machine, that may be removed, when desired.

The beating-wings are made with arms extending from the shaft, attached to which is a bar, G, rounded on the edge or side that comes in contact with the hemp. The intervening space between the bar G and the shaft is filled by a board, or otherwise, thus forming a wing.

The advantage I claim for a wing over a bar alone is, there is much less danger of the hemp catching by partially winding around the bar, and serve also to blow away the shives as they are beaten out.

The rest, D, operating in the inclined slots, may be divided into two or more sections, as shown in fig. 3, so that several persons may work at the same machine—one may be feeding a full bundle, while another may be finishing on the adjoining section.

The springs E E may be made of wood or steel, one end being made fast to the cross-bar of the frame, and the other, striking obliquely against the rest D, keeps the hemp in contact with the beating-wings.

By the arrangement of the rest, D, in the inclined slots *i i*, the hemp will be forced against it with considerable power, as the bearing comes partly in a downward direction, and not entirely on the springs, consequently meeting with more resistance, thus breaking the hemp very effectually, and the wings at the same time blowing or carrying away the shives.

What I claim, and desire to secure by Letters Patent, is—

The beating-wings C, in combination with the rest, D, operating in the inclined slots *i i*, and provided with the springs E, when arranged substantially as described and shown.

In testimony whereof, I have signed my name to this specification in the presence of two subscribing witnesses.

DANIEL F. WALLACE.
